UNITED STATES PATENT OFFICE.

THOMAS C. JOHNSON, OF NEW HAVEN, CONNECTICUT, ASSIGNOR TO
WINCHESTER REPEATING ARMS CO., OF NEW HAVEN, CONNECTI-
CUT, A CORPORATION.

FIREARM.

No. 813,802.

Specification of Letters Patent.

Patented Feb. 27, 1906.

Application filed October 16, 1905. Serial No. 282,883.

To all whom it may concern:

Be it known that I, THOMAS C. JOHNSON, a citizen of the United States, residing at New Haven, in the county of New Haven and State of Connecticut, have invented a new and useful Improvement in Firearms; and I do hereby declare the following, when taken in connection with the accompanying drawings and the numerals of reference marked thereon, to be a full, clear, and exact description of the same, and which said drawings constitute part of this specification, and represent, in—

Figure 1, a broken view, partly in side elevation and partly in vertical longitudinal section, of a gun constructed in accordance with my invention; Fig. 2, a detached view in rear elevation of the compound friction-brake.

My invention relates to an improvement in that class of firearms having non-recoiling barrels and balanced breech-blocks, the object being to provide the breech-block of such an arm with a simple and effective friction-brake for reducing the shock of recoil.

With these ends in view my invention consists in a firearm having certain details of construction and combinations of parts, as will be hereinafter described, and pointed out in the claims.

In carrying out my invention as herein shown I employ a compound friction-brake composed of two split conical sleeves 2 and 3, arranged one within the other, so that their slots 2^a and 3^a do not register. This compound friction-brake is mounted or clasped upon the forward end of a stationary rod 4, the rear end of which is screwed into a supporting-sleeve 5, the forward end of which is screwed into the rear end of the gun-frame 6.

The friction-brake itself is located, as shown, in a conical brake-chamber 7, formed in the rear end of an arm or extension 8, extending rearwardly from the balanced breech-block 9 and formed with a longitudinal passage 8^a, which receives the said rod and which opens at its rear end into the said chamber 7. The said rod 4 is encircled by a breech-block-closing spring 10, the forward end of which impinges against a washer 11, placed against the rear end of the compound friction-brake.

At the time of recoil the tapering walls of the chamber 7 compress and contract the sleeves 2 and 3, so that the former still more closely

hugs the rod 4 and the latter still more closely hugs the sleeve 2. Thus contracted the sleeves are pushed back over the rod, the friction thus developed materially assisting in reducing the shock of recoil by virtually supplementing the weight of the breech-block 9 and reinforcing the spring 4, which returns the breech-block to its closed position after recoil. During this return or forward movement of the breech-block the sleeves 2 and 3 expand and more or less, if not entirely, release their hold upon the rod 4. The non-recoiling barrel 12 is screwed in the usual manner into the gun frame or receiver 6, which is furnished, as shown, with a removable box-magazine 13; but these and other details will vary according to circumstances.

It is apparent that in carrying out my invention some changes from the construction herein shown and described may be made. I would therefore have it understood that I do not limit myself thereto, but hold myself at liberty to make such departures therefrom as fairly fall within the spirit and scope of my invention. Thus in place of a compound friction-brake I might employ a friction-brake consisting of a single conical sleeve arranged to grip the rod 4. This is too obvious to call for illustration or further description.

Having fully described my invention, what I claim as new, and desire to secure by Letters Patent, is—

1. In a gun, the combination with the frame thereof, of a balanced breech-block having a rearward extension containing a brake-chamber, a stationary rod supported at its rear end by the said frame, a friction-brake located in the said chamber and coacting with the said rod to retard the opening movement of the block and so reduce the shock of recoil.

2. In a gun, the combination with the frame thereof, of a balanced breech-block having a friction-brake chamber, a sleeve secured by its forward end in the rear end of the said frame and extending rearwardly therefrom, a rod mounted at its rear end in the rear end of the said cylinder, a breech-block-closing spring located in the said sleeve and encircling the said rod, and a friction-brake located in the said chamber and coacting with the said rod to retard the opening movement of the block and so reduce the shock of recoil.

3. In a gun, the combination with the frame thereof, of a balanced breech-block having a rearward extension containing a brake-chamber, a stationary rod, means carried by the gun-frame at the rear end thereof for supporting the said rod by its rear end, a breech-closing spring encircling the said rod, and a friction-brake located in the said chamber and coacting with the said rod to retard

the opening movement of the block and so reduce the shock of recoil.

In testimony whereof I have signed this specification in the presence of two subscribing witnesses.

THOMAS C. JOHNSON.
